Term of patent 14 years

Int. Cl. D16—01

U.S. Cl. D61—1

Fig. 5

Fig. 4

FIG. 1 is a right side elevational view of a motion picture camera showing my new design;

FIG. 2 is a rear elevational view thereof;

FIG. 3 is a front elevational view thereof, the lower handle portion being omitted for convenience of illustration;

FIG. 4 is a left side elevational view thereof;

FIG. 5 is a top plan view thereof;

FIG. 6 is a right side elevational view of another embodiment of the FIG. 1 motion picture camera on which an alternative lens has been mounted;

FIG. 7 is a front elevational view of the FIG. 6 embodiment.

The crisscross hatching shown in FIGS. 1 and 3-7 denotes a contrasting "pebble grain" pattern finish.

I claim:

The ornamental design for a motion picture camera, substantially as shown and described.
